CLAIM

The ornamental design for a reconfiguring robot car, as shown and described.

DESCRIPTION

FIG. 1 is a top perspective view of a reconfiguring robot car.

FIG. 2 is a front elevational view of the reconfiguring robot car illustrated in FIG. 1.

FIG. 3 is a rear elevational view of the reconfiguring robot car illustrated in FIG. 1.

FIG. 4 is a left side view of the reconfiguring robot car illustrated in FIG. 1.

FIG. 5 is a right side view of the reconfiguring robot car illustrated in FIG. 1; and,

FIG. 6 is a top elevational view of the reconfiguring robot car illustrated in FIG. 1.

The portions of the reconfiguring robot car in broken lines are shown for illustrative purposes only and form no part of the claimed design. The bottom elevational view of the reconfiguring robot car illustrated in FIG. 1 has been omitted, as applicant believes all claimed subject matter is apparent in the illustrations above.
